UNITED STATES PATENT OFFICE.

FURMAN W. VELSOR, OF COLD SPRING, NEW YORK, ASSIGNOR OF ONE-HALF
TO LOUIS M. BRUSH, OF HUNTINGTON, NEW YORK.

DESIGN FOR A PUZZLE-BOARD.

SPECIFICATION forming part of Design No. 27,277, dated June 29, 1897.

Application filed April 8, 1897. Serial No. 631,325. Term of patent 7 years.

To all whom it may concern:

Be it known that I, FURMAN W. VELSOR, a citizen of the United States, residing at Cold Spring, in the county of Suffolk and State of New York, have invented and produced a new and original Design for Puzzle-Boards, of which the following is a specification.

Reference is to be had to the accompanying drawings, forming a part of this specification, in which—

Figure 1 is a plan view of a puzzle, showing my design; and Fig. 2 is an edge view thereof.

The leading feature of my design consists in lines arranged to form a triangular figure and intersecting lines arranged within the triangular figure and forming the outlines of four triangular spaces and six diamond-shaped spaces.

Referring particularly to the drawings, 1 2 3 show the outlines arranged to form a triangle. Extending from the angle-line 1 to the base-line 3 are two parallel lines 4 and 5, which are also parallel with the angle-line 2, and extending from the angle-line 2 to the base-line

3 are two parallel lines 6 and 7, which are also parallel with the angle-line 1. The lines 4 5 intersect the lines 6 7, and with the lines 1 and 2 form the outlines of diamond-shaped spaces 8, 9, and 10, and these several intersecting lines, with the base-line 3, form the outlines of triangular spaces 11 12. From the apex of the lines forming the triangular spaces 11 and 12 lines 13 and 14 extend parallel with the base-line 3 to the angle-line 1 and angle-line 2, respectively. The lines 1, 3, 6, and 13 form the outlines of a diamond-shaped space 15. The lines 2, 3, 5, and 14 form the outlines of a diamond-shaped space 16. The lines 1, 4, and 13 form the outlines of a triangular space 17, and the lines 2, 7, and 14 form the outlines of a triangular space 18.

I claim—

The design for a puzzle-board, substantially as shown and described.

FURMAN W. VELSOR.
